FLUID BLAST CIRCUIT BREAKER

Howard M. Wilcox, Wilkinsburg, Pa., assignor to Westinghouse Electric & Manufacturing Company, East Pittsburgh, Pa., a corporation of Pennsylvania

Application April 2, 1942, Serial No. 437,379

6 Claims. (Cl. 200—148)

The invention relates to a multipole circuit breaker of the fluid blast type wherein the arcs drawn upon interruption of the circuit are extinguished by blasts of arc-extinguishing fluid, such as air blasts derived from a source of compressed air.

An object of the invention is the provision of a multipole circuit breaker having a plurality of mechanically independent pole units or circuit interrupting units and an improved pneumatic system for simultaneously operating the units from a single control valve.

Another object of the invention is the provision of a multipole compressed air circuit breaker having a plurality of mechanically independent pole units and a single electrically controlled valve for simultaneously causing blasts of air to be directed to all of the circuit interrupting units.

Another object of the invention is the provision of a multipole compressed air circuit breaker comprising a plurality of mechanically independent pole units each with an individual blast valve, and a compressed air operating system including a single master air relay valve for simultaneously controlling the operation of all of the blast valves.

Another object of the invention is the provision of an improved multipole compressed air circuit breaker that is simple, reliable in operation and relatively inexpensive to manufacture.

The novel features that are considered characteristic of the invention are pointed out in particular in the appended claims. The invention itself, both as to structure and operation, together with additional objects and advantages thereof, will be best understood from the following detailed description of one embodiment thereof when read in conjunction with the accompanying drawings, in which:

Figure 1 is a front elevational view of a multipole circuit breaker embodying the features of the invention;

Fig. 2 is a side elevational view, partly in section, of the circuit breaker shown in Fig. 1;

Fig. 3 is a sectional view on an enlarged scale of one of the pole unit operating mechanisms, and

Fig. 4 is an enlarged fragmentary view, partly in section, of the lower portion of the breaker showing the master air relay valve and two of the blast valve operating means.

The features of the present invention are illustrated as applied to a circuit breaker of the same general construction as that disclosed in the co-pending application of L. R. Ludwig, B. P. Baker, and J. M. Cumming, Serial No. 437,010, filed

March 31, 1942, and assigned to the assignee of the present invention.

Referring to Fig. 1 of the drawings, the three pole circuit breaker has three separate and mechanically independent circuit interrupting pole units 9 which are mounted in spaced relation on a structural supporting frame 11. The three pole units are of identical construction, and each unit comprises three hollow supporting insulators 13, 15 and 17 secured to the frame in triangularly spaced relation and rising vertically therefrom. Supported on the upper end of the insulators is a casing 19 for housing the contact operating mechanism more clearly shown in Fig. 3. The casing 19 supports a hollow insulator 21 which, in turn, supports a circuit interrupting element 23. A hollow insulator 25 extends upwardly from the element 23 and has a metallic terminal cap 27 secured on its upper end. A stationary contact member 29 (Figs. 1 and 2) extends downwardly from the terminal cap 27 into the circuit interrupting element 23. A movable contact member 31 coacts with the stationary contact member 29 and extends downwardly through the element 23 and through the hollow insulator 21. The lower end of the contact member 31 extends into the casing 19 and is connected to an operating piston of the operating means as shown in Fig. 3. The movable contact member 31 is electrically connected by means of a resilient multipole contact finger assembly 33 (Fig. 3) and through the operating cylinder casting to a terminal 35 (Fig. 2) which is secured to a projection on the lower end of the cylinder casting and which projects outwardly from the casing 19.

Extinction of arcs drawn by the movable contact member 31 upon interruption of the circuit is accomplished by a blast of compressed gas or air directed to an arc-extinguishing structure of the fluid blast type which may be of the form disclosed in the co-pending application of L. R. Ludwig and B. P. Baker, Serial No. 373,856, filed January 1, 1941, U. S. Patent 2,313,159, issued March 9, 1943, and assigned to the assignee of the present invention. Since the present invention is not concerned with the arc-extinguishing unit structure per se, it is believed that the general designation of the arc-extinguishing unit 31 (Fig. 2) located in the interrupting element 23 and which is supplied with a blast of compressed air, will be sufficient for the purpose at hand.

Fluid under pressure, in this instance, compressed air, for extinguishing the arcs and also for the contact operating mechanisms, is stored in a common reservoir or tank 39 mounted with-

in the frame 11. Compressed air is stored and maintained at a predetermined pressure in the tank 39 by a suitable motor driven compressor unit (not shown).

Each movable contact member 31 is operated to opened and closed circuit position by an individual compressed air operating mechanism comprising a double-acting piston 41 (Fig. 3) movable vertically in a cylinder 43 provided in a metal casting 45, there being an individual cylinder casting 45 and compressed air operating piston 41 for each of the three movable contact members 31. Each contact operating mechanism is mounted within its corresponding casing 19, and the three operating pistons and their contact members are adapted to be operated simultaneously to open or closed position, by compressed air from the tank 39, the flow of compressed air for opening and closing the three poles of the circuit breaker being controlled by a single opening valve mechanism 47 and a single closing valve mechanism 49 (Fig. 1).

Referring to Fig. 3, the cylinder casting 45 has an air blast tube 51 formed integral therewith communicating at its lower end with the passage through the hollow supporting insulator 13 (Fig. 2) and communicating at its upper end with the passage through the hollow insulator 21, this tube and the aforementioned passages through the insulators 13 and 21 forming a path for the blast of compressed air which is directed to the circuit interrupting element 23 during circuit opening operations.

A lower cylinder head 53 is secured to the lower end of the operating cylinder, and a shock absorbing assembly indicated generally at 55 is mounted in this cylinder head for absorbing the kinetic energy at the end of a circuit opening operation of the mechanism. A resilient shock absorbing bumper means 57 is mounted in the upper end of the operating cylinder for absorbing the kinetic energy of the moving parts at the end of circuit closing operation. This upper end of the operating cylinder is closed by a cap or head 59 which is threaded into the upper end of the cylinder and the head 59 is provided with an opening for slidably receiving the movable contact member 31 which is of tubular construction. The lower end of the tubular contact member 31 is secured to the operating piston 41 in a central opening provided therein. The operating piston is also provided with a substantially square babbitted opening (not shown) in alignment with the tubular contact member for engaging a centrally disposed twisted square rod 61 which is rotatably mounted in a bearing 63 in the lower portion of the lower cylinder head 53. The twisted square rod extends throughout the entire length of the operating cylinder, the lower end thereof having a cylindrical portion engaging the bearing 63, and a crank arm 65 is rigidly secured to the lowermost end of the rod which projects downwardly from the bottom of the cylinder head 53. The operating piston 41 and the hollow tubular contact member 31 slide telescopically on the twisted square rod 61 as the operating piston is moved upwardly and downwardly in the operating cylinder, and this movement of the operating piston, due to the square opening therein and the twisted construction of the rod, causes the rod to be rotated through an angle in one direction when the piston is moved downwardly to open circuit position, and rotated in the opposite direction when the piston is moved upwardly to closed circuit position. This

movement of the rod 61 is utilized to operate a conventional multipole auxiliary switch (not shown) through the agency of the crank 65 and a linkage 67, 69, 71, and 73.

5 An air passage 75 formed in the upper end of the cylinder casting leads to the upper end of the operating cylinder and is connected through a short section of pipe 77 to the upper portion of an inlet and automatic dump valve assembly 10 79 secured to the side of the cylinder casting. An inlet port 81 of the valve assembly 79 is connected through a pipe 83 (Fig. 2) and the passage through the hollow insulator 15 to an opening air manifold pipe 85 (Fig. 1) common to the 15 three pole units of the circuit breaker. The compressed air for producing simultaneous opening operation of the movable contact members 31 is adapted to flow through the opening air manifold 85 and through the three hollow insulators 15 20 and pipes 83 to the upper ends of the three operating cylinders. The opening air manifold 85 is connected by a pipe 87 to the single opening valve mechanism 47 which controls the simultaneous opening operation of all three poles of the 25 circuit breaker. The single opening valve mechanism 47 is connected by a pipe 89 (Fig. 1) to the air reservoir tank 39.

An air passage 91 formed in the lower end of the cylinder casting 45 is connected through a 30 pipe 93 to the lower section of the automatic valve assembly 79, and a closing air inlet port 95 of the valve device 79 is connected through a pipe 97 and the air passage through the hollow insulator 17 to a closing air manifold pipe 99 (Fig. 1) 35 disposed within the frame 11. The closing air manifold 99 is common to the three pole units, that is to say, it is connected through the passages of the three insulators 17 and pipes 97 to the lower end of the three contact operating cylinders. The closing air manifold 99 is connected by a pipe 101 to the single closing valve mechanism 49 which controls simultaneous closing operation of the three contact members 31 of the 40 circuit breaker. The valve mechanism 49 is connected by a pipe 103 to the air reservoir tank 39.

The opening valve mechanism 47 and the closing valve mechanism 49 are of the same construction as disclosed in the copending application of L. R. Ludwig, et al., Serial No. 431,394, 50 filed February 18, 1942; and assigned to the assignee of the present invention; and only a brief description thereof will be given in this application as the details of construction of these valve mechanisms are not necessary to a complete understanding of the present invention.

Referring to Fig. 1, the opening valve mechanism 47 has a valve element 105 which is biased closed and which is caused to be opened by air pressure in the pipe 89 when the pilot valve of the mechanism is operated upon energization of a solenoid 107. Similarly, the closing valve mechanism 49 has a valve element 109 which is biased closed and which is caused to be opened by compressed air in the pipe 103 when the pilot valve of the mechanism is operated in response to energization of a solenoid 111 associated with the valve.

When the single opening valve mechanism 47 is operated to open position, compressed air flows 70 from the tank 39 through the opening air manifold pipe 85, through the three insulators 15, pipes 83, inlet ports 81 of the valve devices 79 and pipes 77 into the upper ends of each of the three operating cylinders 43 above the operating pistons 41. The flow of compressed air to the ports 81

immediately moves the three slide valve elements of the valve devices 79 to their lower position, thereby connecting the lower ends of the main operating cylinders to atmosphere through exhaust ports 113. The compressed air flowing to the upper ends of the cylinders drives the pistons 41 downwardly to open circuit position, thereby effecting simultaneous opening of the three movable contact members 31 of the circuit breaker. Closing operation of the circuit breaker is produced upon opening of the single closing valve 49. Opening of the valve 49 causes compressed air to flow through the closing air manifold 99 through the three hollow insulators 17, pipes 97, inlet ports 95 and pipes 93 to the lower end of the three operating cylinders 43. The flow of compressed air to the ports 95 causes the slide valve elements of the valve devices 79 to connect the upper ends of the three operating cylinders to atmosphere through the exhaust ports 115. The flow of compressed air to the lower end of the operating cylinders drives the three pistons 41 simultaneously upwardly to their closed positions, thereby effecting closing of the three movable contact members 31.

The construction of the circuit breaker as thus far described in detail above is substantially the same as that disclosed in the aforementioned co-pending application of L. R. Ludwig, B. P. Baker and J. M. Cumming Serial No. 437,010.

A separate air blast valve indicated generally at 117 is provided for each of the three pole units of the circuit breaker. In accordance with the present invention, the three blast valves 117 are operated simultaneously by a compressed air operating system under the control of a single electro-pneumatically controlled air relay valve. Each blast valve 117 includes a housing 119 (Fig. 4), the lower end of which is connected by a pipe 121 to the air reservoir tank 39. The upper end of the blast valve housing 119 is connected by a short section of pipe 123 to the passage of the hollow supporting insulator 13 of its corresponding pole unit. The valve element 125 within the blast valve housing is connected by means of a rock shaft 127 and a rod 128 to a blast valve operating piston 129 disposed in the valve operating cylinder 131. A pair of concentrically disposed helical compression springs 133 mounted in the cylinder 131 between the valve piston 129 and the head of the cylinder act to bias the blast valve element 125 to closed position and normally maintain the valve in closed position. Upward movement of the valve operating piston 129 effects opening of the blast valve.

The lower ends of the three blast valve operating cylinders 131 are connected to a manifold pipe 135 through which compressed air for simultaneously operating the three blast valves is adapted to flow to the lower sides of the valve operating pistons. The manifold pipe 135 is connected by a pipe 137 to the valve chamber of an electro-pneumatically controlled master air relay valve mechanism indicated generally at 139 (Fig. 4). The master control valve 139 is, in turn, connected by a pipe 141 and the pipe 89 to the air reservoir tank 39.

The master air relay valve 139 comprises a valve housing 142 in which is mounted a master valve element 143. The valve element 143 has a stem which is guided for vertical movement in the valve chamber by a sleeve bearing. The valve element 143 is biased to closed position by means of a helical spring 145 concentrically surrounding the valve stem. The upper end of the

spring engages the under side of a collar 147 secured to the top of the valve stem, and the lower end of the spring bears against the spider which supports the guide sleeve bearing for the valve stem. The valve element 143 is adapted to be operated to open position by an air piston 149 which is movably mounted in a small cylinder formed in the upper portion of the valve housing 141. The valve operating piston 149 is biased to its upper position shown in Fig. 4 by means of a helical compression spring 151. The valve piston 149 is adapted to be moved downwardly to effect opening of the valve element 143, by the flow of compressed air through air passages 156 and 153 to the upper side of the piston 149 upon opening of a pilot valve 155. The pilot valve 155 is operated to open position upon energization of a solenoid 157 and is returned to closed position upon deenergization of the solenoid. The valve housing 142 is provided with an exhaust passage 159 which connects the valve chamber to atmosphere when the valve mechanism and its operating piston 149 are returned to the normal position shown in Fig. 4. When the master valve is in its normal closed position, as shown in Fig. 4, the exhaust passage 159 provides an exhaust for air in the lower portions of the three blast valve operating cylinders 131 below the blast valve operating pistons, thereby permitting the blast valves to be quickly returned to closed position immediately after the master control valve 139 is closed. The master valve operating piston 149 is provided with a skirt 161 arranged to close the exhaust passage 159 when the piston 149 is moved downwardly to effect opening of the master valve element 143.

The pneumatic operating system for simultaneously operating the three blast valves has the advantage that it requires only a single master control valve and a single control electromagnet or solenoid for controlling operation of all of the blast valves of the circuit breaker. The arrangement assures that the blast valves will all operate simultaneously even though there is no mechanical tie between the valves, and the pneumatic system is faster in operation and more free from trouble than constructions which utilize a mechanical tie or an electrical tie between the blast valves.

The opening valve mechanism 47 is mechanically interlocked with the operating lever arm 150 (Fig. 1) of the center pole blast valve 117 by means of a lever 152 pivoted on the housing of the opening valve 47 and connected at one end to the opening valve element 105. The interlock includes a projection 154 on the arm 150 of the center pole blast valve which is disposed to block opening movement of the lever 152 and thereby prevent opening of the opening valve 117 except when the center pole blast valve is operated to open position. The interlock thus serves to prevent opening of the opening valve mechanism 47 if the blast valves become inoperative, i. e., fail to open for any reason.

The solenoid 157 of the master air relay valve and the solenoid 107 of the opening valve mechanism are adapted to be energized simultaneously upon opening operations of the breaker, and the solenoid 111 of the closing valve mechanism may be energized either alone, or simultaneously with the solenoid 157 of the master air relay valve 139, on closing operations of the breaker.

The operation of the circuit breaker is briefly as follows: Opening operation of the circuit breaker is initiated by the simultaneous energiza-

tion of the solenoid 107 of the opening valve mechanism 47 and the solenoid 157 of the master air blast control valve 139. Opening of the valve 47 causes compressed air to flow from the tank 39 to the upper ends of each of the three operating cylinders 43 and the compressed air drives the three contact operating pistons 41 simultaneously downwardly to open position, effecting opening at the circuit breaker. The energization of the solenoid 157 of the master control valve 139 effects opening of the pilot valve 155, thereby admitting compressed air from the pipe 141 through the passages 156 and 153 to the top of the valve operating piston 149. Piston 149 is driven downwardly by the compressed air and effects opening of the master valve element 143, whereupon compressed air flows from the pipe 141 into the manifold 135 to the lower sides of the three blast valve operating pistons 129. This flow of compressed air to the lower sides of the three blast valve operating pistons produces simultaneous upward movement of the three valve pistons, thereby effecting simultaneous opening of the three blast valves 125. The opening of the three blast valves 125 causes blasts of compressed air from the tank 39 to be directed to each of the three circuit interrupting elements 23 to blow out the arcs drawn by the three movable contact members 31. Air blasts into the circuit interrupting elements 23 occur prior to the time that the movable contact members 31 separate from their stationary contacts 29 and the air blast is maintained until after the arcs have been extinguished. Upon deenergization of the master valve controlling solenoid 157, the pilot valve 155 returns to closed position and the master valve 143 is returned to closed position by its biasing spring 145 when the valve operating piston 149 is reset to its upper position by the spring 151. When the master valve 143 is thus returned to closed position, the supply of compressed air to the blast valve pistons 129 is shut off and the three blast valves simultaneously are returned to closed position by their biasing springs 133.

Closing operation of the circuit breaker is initiated by the energization of the closing valve solenoid 111. When the closing valve 49 opens, compressed air flows from the tank 39 into the closing air manifold 99 and through the same to the lower ends of the three contact operating cylinders 43. Compressed air simultaneously drives the three operating pistons 41 upwardly to closed position, thereby effecting closing of all three movable contact members 31 into engagement with their stationary contacts. As soon as the closing operation is completed, the solenoid 111 is deenergized and the closing valve is returned to closed position.

While the invention has been disclosed in accordance with the provisions of the patent statutes, it is to be understood that various changes in the structural details and arrangement of parts thereof may be made without departing from some of the essential features of the invention. It is desired, therefore, that the language of the appended claims be given the broadest reasonable interpretation permissible in the light of the prior art.

I claim as my invention:

1. A gas blast multipole circuit breaker comprising a plurality of separate circuit interrupting units each having a pair of separate contacts, operating means for simultaneously operating all of said pairs of contacts, a source of gas under pressure for supplying a blast of gas to each of

said units to extinguish the arcs formed on separation of said contacts, a separate blast valve associated with each of said units for controlling the flow of blast gas from said source to said unit, and a gas pressure operating system for said blast valves, said operating system having a single master control valve for simultaneously controlling operation of said plurality of blast valves.

2. A multipole compressed air circuit breaker 10 comprising a plurality of separate circuit interrupting units each having a pair of separable contacts, operating means for simultaneously operating said contacts, a source of compressed air, air conduits connecting said units to said source 15 of compressed air for conducting blasts of compressed air from said source to said contacts to extinguish arcs formed upon separation of said contacts, a separate air blast valve for each unit for controlling the flow of blast air to said unit, 20 a compressed air operating system for said blast valves including a single master control valve for controlling the operation of said blast valves, and an electromagnet for controlling said master valve.
- 25 3. A multipole compressed air circuit breaker comprising a plurality of separate circuit interrupting units, each having a pair of separable contacts, operating means for said contacts, a source of compressed air, blast air conduits connecting said units to said source of compressed air for conducting blasts of compressed air from said source to said contacts to extinguish arcs formed upon separation of said contacts, a separate air blast valve for each unit for controlling 30 the flow of blast air to said unit, compressed air operating means for said blast valve comprising a master relay valve for simultaneously controlling the operation of said plurality of blast valves, and an electropneumatic pilot valve for controlling 35 said relay valve.

4. A multipole compressed air circuit breaker comprising a plurality of mechanically independent and separate circuit interrupting units each having a pair of separable contacts, operating 45 means for simultaneously operating said pairs of contacts, a source of compressed air, relatively short air conduits of equal length directly connecting said units to said source of compressed air for conducting blasts of compressed air to 50 said contacts to extinguish arcs formed upon separation of said contacts, a separate air blast valve associated with each unit for controlling the flow of blast air to said unit, a compressed air system for operating said blast valves comprising a 55 separate air pressure actuated piston for each valve for opening said valve, and a master air relay valve for simultaneously controlling the operation of said blast valves.

5. A multipole compressed air circuit breaker 60 comprising a plurality of separate and mechanically independent circuit interrupting units each having a pair of separable contacts, compressed air operating means for simultaneously operating said pairs of contacts, a source of compressed air, relatively short air blast conduits of equal length directly connecting said units to said source of compressed air for conducting blasts of compressed air to said contacts to extinguish arcs formed upon separation of said contacts, a sepa- 65 rate air blast valve for each unit for controlling the flow of blast air to said unit, a compressed air operating system for said valves comprising a separate air piston for each valve operable to open said valve, a common air conduit communicating with said pistons, and a master air 70 75

control valve for controlling the flow of compressed air to said common air conduit for simultaneously controlling the operation of said plurality of blast valves.

6. A multiple compressed air circuit breaker comprising a plurality of separate and mechanically independent circuit interrupting units each having a pair of separable contacts, compressed air operating means for simultaneously operating said pairs of contacts, a source of compressed air, air blast conduits connecting said units to said source of compressed air for conducting blasts of compressed air from said source to said contacts for extinguishing the arcs formed upon

separation of said contacts, a separate air blast valve for each unit for controlling the flow of blast air to said unit, a compressed air operating system for said valves comprising an individual 5 cylinder and piston for operating each valve, a common air conduit connected to all of said valve operating cylinders, a pneumatically operated master air relay valve for controlling the flow of compressed air to said common air conduit 10 for simultaneously controlling operation of said blast valves, and an electromagnetically controlled pilot valve for controlling operation of said master valve.

HOWARD M. WILCOX.
